United States Patent Office.

NATHAN S. JOHNSON, OF MAQUOKETA, IOWA.

Letters Patent No. 73,979, dated February 4, 1868; antedated-February 1, 1868.

IMPROVEMENT IN CORN-CULTIVATORS.

The Schedule referred to in these Letters Patent and making part of the same.

Be it known that I, NATHAN S. JOHNSON, of Maquoketa, in the county of Jackson, and State of Iowa, have invented a new and useful Machine for Cultivating Corn; and I do hereby declare that the following is a full, clear, and exact description of the construction and operation of the same, reference being had to the annexed drawings, making a part of this specification, in which—

Figure 1 is a perspective view.

Figure 2 is an end elevation.

Figure 3, a side elevation of a part of the machine.

Figure 4, a plan of the shovel-beams.

I construct the machine as follows: The axles are formed of two short pieces of timber, B B, fig. 1, having attached the four upright standards A A A A, and are connected together at their upper ends by the beam S. The standards A are bored throughout their entire lengths, for the purpose of receiving bolts, by means of which and the nuts E E the entire axle is securely fastened together. Attached to the axle, at the junction of the two outside standards, are two beams, Y Y, placed in a triangular position, and joined to the tongue at G'. To the faces of the two beams Y Y is secured the cross-bar Z. The ends of this bar extend over the sides of the beams, for the purpose of receiving the upper ends of the movable standards or pivots C C. On either side of the standards C C are placed two beams, D D. The two beams D D are connected together at R, fig. 4, by means of a wooden brace, having on its back edge the staple Q. They are also connected together by means of the stirrup P, at each end of the beam. The two shovels H H are secured to the beams by means of short wooden standards and brace-irons, as shown at D, fig. 1. Bolted to the upper surface of the beams Y Y are two levers, extended back, to support the seat-board I. This is suspended by means of the two irons K K, having at their upper ends holes to receive iron pins, resting on the upper surface of the beam S, and forming pivots which allow free lateral motion to the levers and seat-board I. To the under surface of the seat-levers are attached the two short levers L L, having their fulcrum, consisting of two bolts, attached to the axle-bars B B. The opposite ends of the levers pass downward through the staple Q, shown at fig. 4, so that if the seat be deflected to either side, the levers L L will move the shovels H H in a direction contrary to the motion of the seat. The use of the lever M is to raise the shovels by means of the chains O O.

The operation of the machine is as follows: The axle of the machine being constructed as above described, permits the operator, seated in the seat-board I, to have an unobstructed view, through the central opening between the axles, of the corn-hills in advance of the ones operated upon by the shovels, and allows the operator to determine, in advance, the movement of the ploughs that will be necessary to properly cultivate the row of corn. The feet of the operator are placed in the stirrup-irons P, fig. 4. If he wish to move the ploughs to the right or left, with the foot on the stirrup-iron, the seat I will be thrown in the opposite direction, and by its leverage, and the weight of the operator, will cause the shovels to be moved with ease and steadiness.

What I claim as my invention, is—

1. The combination of the two axle-bars B B and the four upright standards A A A A, and cross-beam S, and bolts E.
2. The combination of the seat-board and seat-lever I with the levers L L, shovel-beams D D, and the movable pivot or standard C, substantially as and for the purpose herein specified.

NATHAN S. JOHNSON.
